ALFRED COLERICK PILLINER AND JAMES CHARLES HILL, OF THE OAKFIELD WORKS, NEAR NEWPORT, ENGLAND.

Letters Patent No. 96,262, dated October 26, 1869; patented in England, January 28, 1868.

IMPROVEMENT IN STEAM-ENGINEERY FOR MOTIVE-POWER.

The Schedule referred to in these Letters Patent and making part of the same.

To all to whom it may concern:

Be it known that we, ALFRED COLERICK PILLINER, of the Oakfield Works, near Newport, in the county of Monmouth, England, civil engineer, and JAMES CHARLES HILL, of the same place, iron-master, subjects of the Queen of Great Britain, have invented or discovered new and useful "Improvements in Machinery for Obtaining Motive-Power, applicable also to measuring, raising, exhausting, forcing, and compressing fluids;" and we, the said ALFRED COLERICK PILLINER and JAMES CHARLES HILL, do hereby declare the nature of the said invention, and in what manner the same is to be performed, to be particularly described and ascertained in and by the following statement thereof; that is to say—

This invention has for its object improvements in machinery for obtaining motive-power, applicable also to measuring, raising, exhausting, forcing, and compressing fluids.

The apparatus consists of a casing in the form of two parallel cylinders placed side by side, and opening, the one into the other, and enclosed by covers at the ends. At the point of contact of the two cylinders is a fixed roller, or other fulcrum, on which a partition is able both to rock and reciprocate or slide. This partition is of a peculiar form. It has at each end a cylindrical, or nearly cylindrical head, and a stem connects them. Passing through the end cover of one of the cylinders is an axis with a crank-arm upon it, carrying a crank-pin, which is embraced by a bearing in one of the cylindrical heads of the partition, and concentric with it. The radius of the crank-arm added to the radius of the cylindrical head should, together, equal the radius of the cylindrical casing in which they work, so that the cylindrical head of the partition will always be in contact with the casing on the side toward which the crank is standing, and as the crank travels round, this line of contact will also travel round within the casing. Radial packing-strips, furnished with springs or other packings, are fitted into the cylindrical head, so that the steam or fluid may not be able to pass the line of contact. The covers at either end of the casing fit closely to the double-headed rocking partition. The head at the end of the rocking partition opposite to the crank, or on the other side of the fulcrum, in a similar way, is always in contact with the casing, and the line of contact travels round within it in a similar manner. It will, however, be found that either the head of the partition or the casing will require to differ somewhat from the cylindrical form. The inlet and outlet-passages are formed in the casing at the junctions of the two cylinders, and on opposite sides of the rocking partition, or in one or both covers. The partition thus constantly divides

the casing into two parts, in one of which is the inlet, and in the other the outlet, so that as the fluid cannot pass from one to the other without the partition being moved, the fluid, if under pressure, gives this motion to the partition, and so drives the crank-axis; or if the axis be driven, the apparatus will draw fluid in at one passage and expel it by the other.

Figure 1 is a vertical section,

Figure 2 is a horizontal section, and

Figure 3 is a front view of the apparatus arranged as for a water-meter, but its form will be substantially the same, whatever the purpose for which it is employed.

a a is the casing of the apparatus. It has an inlet-passage at *a¹*, and an outlet at *a²*.

b is a bolt passing through the casing from side to side, and having upon it the roller or cylinder *b¹*, which serves as the fulcrum for the double-headed partition *c* into a slot, *c¹*, in which the fulcrum is received.

c² is a socket or bearing formed within one of the heads of the partition *c*, and in the centre of this head it receives the crank-pin *d*, carried by an arm, *d¹*, on the axis *d²*, which passes out through the front of the casing, in the centre of one of the cylinders of which it is composed.

c³ c⁴ are packing-strips of metal. They are fitted into radial grooves in the heads of the partition, in such manner that they can move out and in a short distance, and they are furnished with springs tending to press them outward from the centre, so as to cause them to bear against the sides of the casing, and so make a tight joint against it, as in succession they are brought up into contact with the casing by the movement of the partition. Packing is also provided between the end plates of the casing and the sides of the partition.

e is the pipe by which the water comes to the meter, after the dash-plate *f* has broken the force of the stream. It passes through the filter-plate *g*, and so to the inlet-aperture *a¹*.

h is a passage, by which any mud which may accumulate is blown out from time to time.

When the machine is not required to work with water, but with steam, air, or other fluid, the parts *g* and *h* may be dispensed with.

On the axis *d²*, when the apparatus is used as a meter, two metal disks are mounted, having an India-rubber ring between them, which bears on the surface of the face-plate *i*, on an axis, *i¹*, carrying a worm giving motion to a train of counting-wheels.

The India-rubber ring is compressible by means of a screw-nut, and thus the speed of the registering-train can be slightly varied sufficiently for the purposes of accurate adjustment. Where the apparatus is

required to be actuated by fluid under pressure and to drive machinery, the counting-gear is not required, and driving-pulleys, spur-wheels, or similar instruments, are mounted on the axis a^2 , to transmit the power from it to the machinery to be driven.

It is not essential that the two cylinders of the casing should be of the same size. It is sometimes advantageous to make that in which the crank works larger than the other.

The apparatus may be varied by applying a crank to each head of the partition, and connecting them so that they may revolve in opposite directions, either by toothed wheels or otherwise, and dispensing with the fulcrum.

The inlet-passage may be arranged to pass through the stem of the rocking partition, and, where the apparatus is worked by steam under pressure, expansion-valves may be applied, or the partition itself may form its own cut off.

Figures 4 and 5, on sheet 2 of the drawings hereunto annexed, show an apparatus for obtaining motive-power, in which the inlet-passage is formed through the stem of the partition, and also in which the steam is cut off at half stroke, or thereabout, the partition itself forming the cut-off valve. In these figures the same letters of reference are used to indicate like parts to those shown on sheet 1, so that it is unnecessary again to describe them.

The slot or hollow chamber c^1 of the stem c is kept full of steam by steam passing in through the inlet-passage a^1 , and the steam passes from this chamber alternately through the two passages a^3 into the two cylinders of which the casing a is composed.

When the parts are in the position shown at fig. 4, steam is acting expansively in the larger cylinder, whilst the full pressure of steam is acting in the smaller cylinder.

As soon, however, as the crank-pin comes in a line with the central roller b^1 , the stem c has been brought into such a position that steam will be cut off from

the smaller cylinder, and immediately afterward steam will be admitted into the larger cylinder. Subsequently, at the completion of another half stroke, steam will similarly be cut off from this cylinder, and so on continuously.

Having thus described the modes in which we have contemplated the application of the principle of our invention, we declare that we are aware, that previous to our invention, rotary engines and rotary pumps had been constructed with a casing similar to ours, and with two revolving pistons, revolving in the cavity of the casing and combined together. We are also aware that the pistons have been constructed to revolve eccentrically in the cavity of the casing.

We do not wish to be understood as claiming to have invented such previous constructions; but

What we claim as our invention, and desire to secure by Letters Patent, is—

The combination of the casing with the double-headed rocking partition constructed with fixed heads, the hole constructed to operate substantially as before set forth.

Also, the combination of the casing, the double-headed rocking partition, the crank-pin, the crank-arm, and the crank-axis, passing through the front of the casing, the whole constructed to operate substantially as before set forth.

Also, the combination of the casing, the double-headed rocking partition, the filter-plate, and the dash-plate, the whole constructed to operate substantially as before set forth.

ALF. C. PILLINER.
J. C. HILL.
